UNITED STATES PATENT OFFICE.

DAVID GESSNER, OF WORCESTER, MASSACHUSETTS.

NAPPING-MACHINE.

1,240,194.

Specification of Letters Patent. Patented Sept. 18, 1917.

Application filed August 28, 1913. Serial No. 787,051.

To all whom it may concern:

Be it known that I, DAVID GESSNER, a citizen of the United States, residing at Worcester, county of Worcester, State of Massachusetts, have invented certain new and useful Improvements in Napping-Machines, of which the following is a specification.

My invention consists in certain improvements in planetary cloth napping machines and refers more particularly to the manner of mounting the napping rolls in the drum-heads, my object being to simplify these mountings and thereby secure better results in the working of such machines.

The invention consists in the improvements to be fully described hereinafter and the novelty of which will be particularly pointed out and distinctly claimed.

I have fully and clearly illustrated my invention in the accompanying drawings to be taken as a part of this specification and wherein—

Figure 1 is a cross section of a napping drum containing my improved mounting of the napping rolls;

Fig. 2 is a side view of one end thereof, with certain parts shown in section;

Figs. 3, 4, 5, 6, 7, 8 and 9 are details thereof;

Figs. 10, 11 and 12 show modifications of certain parts;

Figs. 13, 14 and 15 show in partial section a modification of my improved method of mounting the napping rolls; and

Figs. 16 and 17 show details thereof.

Referring to Figs. 1 and 2, A is one of two end-frames of a napping machine, B are the bottom cross girds, B' are the top cross girds, and C are the tie rods uniting the end frames. D is a main bearing on top of one of the frames A, for holding one end of the drum shaft E, to which are keyed drum heads F, one being shown in the drawing, which head is formed with peripheral openings or seats, containing U-shaped open bushings f, for holding the napping roll gudgeons or journals g, of the napping rolls h, said bushings being held in place by screws s' threaded through said bushings into the periphery of the head. The rolls may be driven in any suitable manner, as by a circular rack or internal gear E' mounted on the shaft E and meshing with gears

E'' on the ends of the gudgeons of said rolls. A traveling grease ring i is arranged around the napping roll journals g consisting preferably of two sections and united by two coupling pieces l into one complete ring. One of these traveling grease rings 60 is placed around the journals g at either end of and close to the napping roll bodies. The traveling grease ring is supported solely by and is free to move about the journals, which form its only support. However, when it is 65 desired to remove a section piece l from the ring i, cams C', which turn loosely upon the tie rods C, are moved with their high part upward until they touch or pinch against the ring i, thus supporting it, for the time being, 70 from below, as shown in Fig. 1 while the machine is at rest. When the section piece l has been inserted and bolted in place by screws m, the cams are brought out of touch again with the ring i by simply turning the 75 cams until their heavy or high parts point downward, as shown in Figs. 3 and 5, whereupon the rings i are free again, once more to revolve upon and with the journals g when the napping drum is set in motion. 80

I will now describe means for supplying suitable lubricant to the grease ring to be distributed thereby to the gudgeons of the napping rolls:

The drum shaft E has an axial hole or 85 passage o drilled into it from its extreme end toward the middle of the machine, which hole extends far enough in to connect with a tube n set in one of the heads F and extending from the hub of the head outward 90 through its rim, until its end almost touches the traveling grease ring around the journals g of the napping rolls h. By attaching a compression cup, not shown, to the outer end of the drum shaft E a suitable lubricant 95 is forced through the hole or passage o; and out from the tube n upon the traveling grease ring i, from which it spreads to the journals of the napping rolls. A crook n' is put into the tube n near its outer end to 100 check the flow of the lubricant, which would otherwise be increased by the thrust imparted to it by centrifugal force when the machine is set in motion.

A projection, preferably in the form of a flange, or lip p (see Figs. 2 and 9) reaches out from the ring i over the end of the napping roll bodies of the rolls h, but clearing

them by about a sixteenth of an inch, so that the rolls cannot contact with this lip during the operation of the machine. Fastened to the drum heads F, and placed directly under each napping roll body, are the cups q made of pressed steel, which reach out from the drum heads and under the napping roll bodies to about the same extent as the lip p of the ring i over-reaches the napping roll bodies on the opposite side. These cups q, too, clear the rolls about one sixteenth of an inch, in the ordinary operation of the machine.

Should at any time a journal of one of the rolls break, either through crystallization of the metal in it, or through some other accident, the lip p, on the traveling ring i, will prevent the roll from flying outward, and the cups q will prevent the damaged roll from contacting with its neighbors, or from dropping inward, as the machine slows up before coming to a stop, and thus the general destruction of rolls will be prevented, which destruction now is unavoidable in all napping machines of which I am aware. It is well known that when a journal of a napping roll breaks it always gives way at the inner end near the napping roll body, and the breaking of just one journal during the operation of the machine often means the destruction of every other roll in the entire napping roll drum during the mix-up of flying rolls.

Instead of using the cups q, the drum heads F may each be provided with a circular lip or flange z projecting inward over the bodies of the rolls, as in Figs. 10 and 11, to stop the napping rolls from dropping inward, with T-bolts s secured to the drum heads between each pair of napping rolls, to prevent their contacting sidewise, in case an accident should happen, as above mentioned. While I prefer the use of the pressed steel cups q, still, injury to the rolls will be effectually prevented by the construction shown in Figs. 10, 11 and 12.

While in Figs. 1 and 2 the traveling grease ring i surrounds the journals of the napping rolls where they are held in the U-shaped bushings f in the heads F, the ring i, as shown in Figs. 13 and 15, is clapped around the gudgeons or journals alongside of the heads F directly inside of them and between the head and the napping roll bodies. For this reason the gudgeons or journals g are made correspondingly longer and the cups q are extended in proportion so as to still project under and partially around the napping roll bodies, so when in case of accident a journal should break, the broken roll cannot contact with its neighbors or drop inside the drum when the machine is being brought to rest. The ring i is lubricated, as before, through a crook-necked tube n, connecting with a hole or longitudinal opening, o, with-

in the drum shaft E to the outer end of which a lubricating cup is attached.

In the construction shown in Figs. 13 and 15 the roll may be driven in the same manner as described for Figs. 1 and 2, the rolls having gears E'' for this purpose, as shown in Fig. 13.

For lubricating the journals of the napping rolls, where they are held in the U-shaped bushings f in the heads F, a grease band v, preferably made of felt, is slung around them and buckled together at y (Fig. 15). A loop w, attached to the band v, is slipped over a pin t, screwed into the side of grease ring i, whereby the grease band is carried around the journals by the traveling grease ring i as soon as the machine is set in motion. The grease felt band v, having once been saturated with a lubricant, will communicate the same to all the journals by contact. So much of the pressed steel cups q, as is located directly under the journal of a napping roll, and not under the napping roll body itself, may be lined with a layer of soft felt or a similar substance (see Fig. 17) to catch any surplus grease squeezed against the ring i from the crook-necked tube n.

k is a flat piece of steel, or a feather, inserted into the side of drum head F, and projecting outwardly from its periphery to cause the traveling grease ring i to always travel the same path between these feathers k and the ends of the napping roll bodies h.

What I claim and desire to secure by Letters Patent of the United States is:—

1. In a planetary napping machine, in combination, a head, a circular series of napping rolls having gudgeons journaled in said head, and a ring surrounding said gudgeons and having a lip overlying the ends of the bodies of said rolls.

2. In a planetary napping machine, in combination, a head, a circular series of napping rolls having gudgeons journaled in bearings in said head, a ring surrounding said gudgeons, and means for preventing both inward and outward movement of the rolls in case of breakage of the gudgeons.

3. In a planetary napping machine, in combination, a head, a circular series of napping rolls having gudgeons journaled in bearings in said head, a ring surrounding said gudgeons, and stop means carried by the head and located between the rolls to prevent the rolls contacting each other in case of breakage of the gudgeons.

4. In a planetary napping machine, in combination, a head, a circular series of napping rolls having gudgeons journaled in said head, a ring surrounding said gudgeons, means for preventing inward and outward movement of the rolls in case of breakage of the gudgeons, and stop means on the head and located between the rolls

to prevent the rolls contacting each other in case of said breakage.

5. In a planetary napping machine, in combination, a head, a circular series of 5 napping rolls having gudgeons journaled in bearings in said head, a ring surrounding said gudgeons, and means for supporting the rolls out of contact with each other in event of breakage of the gudgeons.

10 6. In a planetary napping machine, in combination, a head, a circular series of napping rolls having gudgeons journaled in bearings in said head, a ring surrounding said gudgeons and having a lip overlying the ends of the bodies of the rolls, and means located inside the series of rolls and projecting beneath the bodies thereof to support the same in event of breakage of the gudgeons.

15 7. In a planetary napping machine, in combination, a head, a circular series of napping rolls having gudgeons journaled in bearings in said head, a ring surrounding said gudgeons and having a lip overlying the bodies of the rolls, and a cup-shaped support located beneath each roll to support the same in case of breakage of its gudgeon.

20 8. In a planetary napping machine, in combination, a head, a circular series of napping rolls having gudgeons journaled in bearings in said head, and a flange upon the said head and projecting over the bodies of the rolls to hold the rolls out of contact with each other in case of breakage of a gudgeon.

25 9. In a planetary napping machine, in combination, a head having open bearings, a circular series of napping rolls having gudgeons journaled in said bearings, a ring surrounding said gudgeons between the said head and the bodies of the rolls, and a grease band surrounding said gudgeons over the bearings.

30 10. In a planetary napping machine, in combination, a head having open bearings, a circular series of napping rolls having gudgeons journaled in said bearings, a ring surrounding said gudgeons between the said head and the bodies of the rolls, a grease band surrounding said gudgeons over the bearings, and means whereby said band rotates about said gudgeons.

35 11. In a planetary napping machine, in combination, a head having open bearings, a circular series of napping rolls having gudgeons journaled in said bearings, a ring surrounding said gudgeons between the said head and the bodies of the rolls, a grease band surrounding said gudgeons over the bearings, and means connecting said ring and grease band whereby they rotate together.

40 12. In a planetary napping machine, in combination, a head having open bearings,

a circular series of napping rolls having gudgeons journaled in said bearings, a ring surrounding said gudgeons between the said head and the bodies of the rolls, a grease band surrounding said gudgeons over the 70 bearings, and means for supplying a lubricant to said ring and grease band.

45 13. In a planetary napping machine, in combination, a head having open bearings, a circular series of napping rolls having 75 gudgeons journaled in said bearings, a ring surrounding said gudgeons between the said head and the bodies of the rolls, a grease band surrounding said gudgeons over the bearings, and means for supplying a lubricant to said ring and grease band, said means comprising an axial opening through said shaft and a tube connected to said opening at one end and opening at its other end against said ring.

50 14. In a planetary napping machine, in combination, a frame, a head, a circular series of napping rolls having gudgeons journaled in said head, a ring surrounding 80 said gudgeons and supported thereby, and means mounted on the frame and adapted to support said ring when the machine is at rest.

55 15. In a planetary napping machine, in combination, a head, a circular series of 85 napping rolls having gudgeons journaled in said head, a ring surrounding said gudgeons and supported thereby, and cam means to support the ring when the machine is at rest.

60 16. In a planetary napping machine, in combination, frame, tie rods, a head journaled in said frame, a circular series of napping rolls having gudgeons journaled in said head, a ring surrounding said gudgeons and supported thereby, and rotatable 105 cams mounted on said tie rods for supporting the ring when the machine is at rest.

65 17. In a planetary napping machine, in combination, a head having bearings, a circular series of napping rolls having gudgeons journaled in said bearings, and a ring surrounding said gudgeons between the head and the bodies of the rolls and having 110 means projecting over the ends of the bodies of the rolls to prevent outward movement of the rolls in event of breakage of the gudgeons.

70 18. In a planetary napping machine, in combination, a head, a circular series of napping rolls having gudgeons journaled in bearings in said head, and a ring surrounding said gudgeons and having means projecting over the ends of the bodies of the 115 rolls to prevent outward movement of the rolls in event of breakage of the gudgeons.

75 19. In a planetary napping machine, in combination, a head, a circular series of napping rolls having gudgeons journaled in 120

bearings in said head, and a ring surrounding said gudgeons and having an annular part projecting over the ends of the bodies of the rolls to prevent outward movement of the rolls in event of breakage of the gudgeons.

In testimony whereof I have hereunto

signed my name in the presence of two subscribing witnesses.

DAVID GEESNER.
